UNITED STATES PATENT OFFICE.

OSCAR GEORGE HAUSNER, OF WEBSTER GROVES, MISSOURI.

ORDER CARD.

Application filed June 7, 1926. Serial No. 114,152.

The object of my invention is to devise an order card to be used in ordering merchandise. A more particular object is to make an order card to be used particularly by the 5 housewife in ordering food products, particularly dairy products, and more specifically milk, cream, etc. In ordering milk, cream, etc., the purchaser rarely sees the salesman. Since a written order must be 10 made and placed so that it will be found and understood by the salesman, since practically all milk, etc., is sold in bottles, and since the empty bottles are returned to the salesman, my device is so formed as to have 15 a body portion upon which the order is placed and a projection which may be inserted in the neck of the empty bottle. The body portion is sufficiently large that it will not pass into the neck of the bottle. My 20 device is so formed that no pencil or writing instrument is necessary to indicate the order that is desired. The advantages thus far described accrue to the purchaser. The advantage to the salesman is that the designations on the body portion of my device suggest the different products that the salesman is offering to sell. In this way the sales 25 are materially increased because the different products that are sold are always placed 30 before the purchaser at each time that an order is given. My device is made in one piece that can be easily, simply and cheaply manufactured and that may be used indefinitely. The device is also provided with 35 means for hanging on a nail when not in use. It is provided with pins or brads for indicating both the character of the product desired as well as the quantity. The character and quantity are indicated by the insertion of a single pin in a particular perforation. 40

With these and other objects in view, my invention has relation to certain novel features of construction and arrangement of 45 parts as will be hereinafter more fully described, pointed out in the claim and illustrated in the drawings in which,

Fig. 1 is a front elevation of my device and in which—

Fig. 2 is a rear elevation of my device, showing the back of Fig. 1.

Numerals 3 designates the body portion of my device, and numeral 4 an integral projection therefrom. My device may be made 55 of celluloid, aluminium, or any similar material that is light in weight, cheap, and that will not absorb moisture readily and is durable and will permit the printing of designations thereon. The projection 4 is of such width that it may be easily inserted in the neck of a milk bottle and of a length sufficient that when it is inserted in a milk bottle that the body portion 3 will be sustained in substantially a vertical position. The body portion is preferably 60 made either circular or polygonal in shape. The drawing shows the body portion circular in shape. On the front of the body portion, as indicated in Fig. 1, radial lines are drawn so as to divide the area in as 65 many segments as desired. These radial lines terminate in the circle 4'. Numeral 5 designates a second circle of lesser radius than the circle 4. In each segment between the circles 4 and 5, is written the word 70 "Quantity". Numeral 6 designates a third circle of lesser radius than the second circle 5. In each segment between the second and third circles are placed perforations 7. These perforations 7 are all positioned at 75 the same radial distance from the center of the body 3 and each perforation is numbered in each segment. In Fig. 1, I have shown three such perforations in each segment and each perforation is numbered 1, 80 2, and 3. In the segments between the center of the body 3 and the third circle 6 are designated the different products sold by the salesman and the quantity of each product sold by the salesman. For instance, 85 in one segment is placed the designation "Butter" and the quantity "Pounds" and in another designation, "Certified milk" and quantity "Quarts". In the projection 4 is formed a line of perforations 8. Numerals 90 9 designate pins or brads that may be placed in the line of perforations 8 when not in use. Numeral 10 designates a perforation near the end of the projection 4, presenting 95 means for hanging my device on a nail 100 when not in use. On the reverse side of my device are printed the directions for using my device. On the projection 4 may be printed the name of the dairy company. My device may be used by the selling company as an advertisement. The operation 105 of my device is as follows: In order to indicate an order both in kind and quantity by my device, one of the pins 9 is removed from the line of perforations 8 110 and placed in the proper perforation in the perforations 7. For instance, if it was

desired to place an order for three pounds of butter, the pin would be placed in perforation 3 in the segment designated "Butter, pounds". If it were desired to order two pints of certified milk, the pin would be placed in perforation 2 of perforations 7 in the segment designated "Certified milk, pints". In this way by the use of several pins, several orders may be placed. The pins not in use remain in the line of perforations 8. In order to secure the pins in the perforations, the ends are bent over as shown by 11 in Fig. 2.

What I claim and mean to secure by Letters Patent is—

An order card comprising a circular body

portion and a projection so proportioned as to permit its insertion into a bottle, the projection secured to the body portion, the face of the body portion being radially divided into sections, each section having a merchandise indication and a quantity indication and a row of perforations bearing numerical indications, pins of such size as to permit their insertion in the perforations of the row in each segment, said projection having perforations therein for the reception of said pins.

In testimony whereof I affix my signature.

OSCAR GEORGE HAUSNER.
